UNITED STATES PATENT OFFICE.

ZIVA POPIN, OF NEW YORK, N. Y.

HEATER FOR WAVING HAIR.

1,416,750.

Specification of Letters Patent. Patented May 23, 1922.

Application filed May 17, 1919. Serial No. 297,764.

To all whom it may concern:

Be it known that I, ZIVA POPIN, residing at New York, in the county and State of New York, have invented certain new and 5 useful Improvements in a Heater for Waving Hair, of which the following is a specification.

This invention relates to a new and improved heater adapted to be used in the art 10 of permanent hair waving.

One of the objects of the invention is to provide a heater which may be utilized in imparting what is known as a permanent set or curl, in what is known as a Marcel wave, 15 that is to say, a wave in which the curl is imparted to a lock or tuft of hair in a direction at right angles to its length, in contradistinction to a spirally formed curl or wave, such as is imparted in the now utilized processes of permanent hair waving.

A further object of the invention is to provide a heater which conforms to the shape of the head, whereby the inner end of the wave to be imparted to the lock of hair 25 will terminate at equal distances from the scalp.

A further object of the invention is to provide a heater of the above character, which may be more easily positioned upon 30 the hair wound upon a curler than has been possible to do with heaters as hitherto constructed.

Other objects and aims of the invention, more or less specific than those referred to 35 above, will be in part obvious and in part pointed out in the course of the following description of the elements, combinations, arrangements of parts and applications of principles, constituting the invention; and 40 the scope of protection contemplated will be indicated in the appended claims.

In the accompanying drawing, wherein I have illustrated a preferred form of embodiment of my invention:

45 Figure 1 is a plan view of the interior of the heater in open position, electrical wiring being shown in dotted lines.

Figure 2 is an elevational view of the upper side of the heater.

Figure 3 is a sectional view taken substantially on the line 3—3 of Figure 2, looking in the direction of the arrow; and

Figure 4 is a sectional view showing the manner in which the heater is employed in carrying out my improved process.

Referring now to the drawing, wherein similar reference characters refer to similar parts throughout the several views thereof, the reference numeral 1 denotes one part of the heater, and 2 the other part thereof, 60 each of said parts being of semi-cylindrical form, as shown, and hinged together, as at 3. Each part comprises an outer hollow shell 4, which is preferably formed of a light material, such for instance as aluminum, and located in each shell is a metallic core 5, each core having positioned thereon a coil of resistance wire, as indicated at 6. Pairs of leading-in wires 7 and 8 are connected with the resistance wire on each 70 core, so that when the circuit is closed through the leading-in wires, the resistance wires will heat the cores, whereby the surrounding parts will be heated thereby. Strips of insulating material 9 and 10 are 75 shown interposed between the lateral sides of the core and the ends of the chambers within the shell 4, thereby preventing the core from being displaced from its normal position within the shell.

80 The shell 2 at its free edge is preferably provided with a slot 11, which is adapted to receive a tongue 12 formed upon the free edge of the shell 1, as indicated in Figure 3 of the drawings. The parts are locked in 85 the position shown, as by means of a resilient wire clip 13, which is pivoted at 14 to the shell 4, and which is adapted to be positioned about the hinged parts, as indicated in Figures 2 and 3. One of these wire 90 clips is provided at each end of the device, as indicated in Figure 2.

95 It will be seen, therefore, that these clips serve to resiliently hold the hinged parts in close relation about the hair to be treated. It will also be noted that the parts 1 and 2 are arc-shaped in form, each having the concaved part 15 and the convexed part 16, so

that when the hinged parts are in close position they have the form of a bent tube; the concaved part being intended to conform to the shape of the hair of which the wave or 5 curl is to be imparted.

The use of my improved device is illustrated in Figure 4 of the drawings, in which figure it will be noted that the hair indicated at 17 is wound upon a curler 18, such 10 as illustrated in my co-pending application Serial Number 297,765.

Upon the curled hair is positioned a moistened impregnated carrier 19, such as illustrated in my co-pending application, 15 Serial Number 297,767, said impregnated carrier being wrapped about the hair, and the free ends extended between the free ends of the respective parts of the heater with the strand of hair between the ends of the 20 carrier, as clearly shown in the drawings. Over the curled hair, and the impregnated carrier, is positioned a split tube 20, which is preferably composed of a pasteboard tube.

With the parts in the position shown, the 25 wire clips 13 are swung into the position shown in Figures 2 and 3 of the drawing, thereby resiliently locking the parts together. The tongue and groove construction of the free ends of the cylindrical shell parts 30 serve as a baffle to prevent the heat from escaping toward the scalp, the latter being further protected against the heat by means of the protective device or shield indicated at 21, which is of the construction shown in 35 my co-pending application Serial Number 297,766.

It will be understood, of course, that in actual use the interior parts of the device 40 will be more closely associated with the hair, impregnated carrier and the tube in the interior wall of the heater will be in close engagement; the slight separation of these parts shown in Figure 4 being in the interests of clearness of illustration.

45 It will accordingly be seen that I have provided a device well adapted to attain, among others, all the aims and objects above pointed out, in an extremely simple manner. The divided construction of the 50 heater enables it to be readily positioned upon and removed from the hair to be treated. It will also be noted that the cable 22, which is composed of the leading-in wires 7 and 8, is disposed midway of the length of the heater, 55 whereby when the same is suspended it will be nicely balanced, thereby relieving any strain upon the hair.

As many changes could be made in this 60 construction without departing from the scope of the following claims, it is intended that all matter contained in the above description or shown in the accompanying

drawing shall be interpreted as illustrative only and not in a limiting sense.

Having thus described my invention what I claim as new and desire to secure by Letters Patent is:

1. A heater comprising a pair of semi-cylindrical parts hinged together, each part being provided with a heating element, the free meeting edges of said parts being so constructed as to permit a layer of hair to pass therebetween. 70

2. In a device of the class described, in combination, a pair of semi-cylindrical parts hinged together and adapted when in closed position to embrace a lock of hair, 75 each of said parts being provided with a heating element, the free meeting edges of said parts being so constructed as to permit a layer of hair to pass therebetween.

3. In a device of the class described, in combination, a pair of semi-cylindrical parts hinged together and adapted when in closed position to embrace a lock of hair, 85 each of said parts being provided with a heating element, and means for resiliently holding said parts in closed position, so that a space may be provided between the free meeting edges to permit a lock of hair to extend therebetween. 90

4. In a device of the class described, in combination, a pair of hollow semi-cylindrical, hinged shells, each of which is provided with a heating element, means for electrically heating each of said elements, and means for resiliently holding adjacent edges of said hinged shells in closed position, the construction being such that a lock of hair may extend between the adjacent free edges 100 of said shells. 95

5. In a device of the class described, a pair of hollow shells, each shell being semi-circular in form, and each shell being curved longitudinally of its length, means for hinging said shells together, a heating element in each shell, and means for supplying a current to each of said heating elements. 105

6. In a device of the class described, a pair of hollow shells, each shell being semi-circular in form, and each shell being curved longitudinally of its length, means for hinging said shells together, a heating element in each shell, means for supplying a current to each of said heating elements, and means for resiliently holding said shells together. 110 115

7. In a device of the class described, a pair of hollow shells, each shell being semi-circular in form, and each shell being curved longitudinally of its length, means for hinging said shells together, a heating element in each shell, means for supplying a current to each of said heating elements, means for resiliently holding said shells together, one 120

of said shells at its free end being provided with a longitudinally extending groove, and the other at its free end being provided with a longitudinally extending tongue adapted

5 to fit into said groove.

8. In a device of the class described, a pair of hollow cylindrical shells, said shells having adjacent edges hinged together, so that when the shells are in closed position they

10 form a circular bore, the free edge of one of said shells being provided with a groove, and

the free edge of the other of said shells being provided with a tongue, and means for resiliently urging said shells into engagement.

15

In testimony whereof I affix my signature in the presence of two witnesses.

ZIVA POPIN.
